UNITED STATES PATENT OFFICE.

LUCINDA C. HINKLE, OF SHREVE, OHIO.

FENCE-WIRING CLAMP.

No. 928,127.

Specification of Letters Patent.

Patented July 13, 1909.

Application filed January 13, 1909. Serial No. 472,031.

To all whom it may concern:

Be it known that I, LUCINDA C. HINKLE, a citizen of the United States, residing at Shreve, in the county of Wayne and State 5 of Ohio, have invented certain new and useful Improvements in Fence-Wiring Clamps, of which the following is a specification.

My invention relates to clamps for engaging wire fabric fencing, and has for its 10 object the provision of an improved device consisting of two clamp-bars held together by pins secured to one bar engaging apertures in the other bar, said pins being provided with slots of graduated length to receive 15 a wedge-key to clamp the bars together, the pins being provided with rectangular shoulders that fit similarly formed recesses in a head on the one bar, while the other bar is formed with a groove to receive 20 said head, said head and groove also operating to flex the wire fabric to more securely hold it between the bars.

My invention will be described in detail hereinafter and illustrated in the accompanying drawings, in which—

Figure 1 is a side view in elevation of my improved clamp, showing it in engagement with the wire fabric; Fig. 2, an edge view, showing the pins in longitudinal section; 30 Fig. 3, a cross-section of the clamp through one of the pins; and Fig. 4, a view of the bar to which the pins are secured.

In the drawings similar reference characters indicate corresponding parts throughout 35 the several views.

1 and 2 indicate the two bars constituting the two clamp members, the bar 1 having a bead 3 that engages the groove 4 in the bar 2 when the device is in operation and serves 40 to flex the wire fabric A so as to more securely hold it.

5 indicates pins formed with rectangular shoulders 6 that engage rectangular depressions 7 in bead 3 and threaded ends 8, that 45 extend through holes 9 in bar 1, and 10 nuts engaging said threaded ends to secure the pins in place. The other ends of pins 5 engage holes 11 in bar 2, each of said pins being provided with a slot 12 graduated in 50 length with relation to the slot in each of the other pins to receive a wedge key 13, that is inserted in the slots from one end of the

clamp, preferably the upper, the slot in the pin at that end of the clamp being the longest, so as to receive the widest portion of the 55 key 13, while at the other end the slot is the shortest and the intermediate pins have slots graduated as stated to snugly fit the clamp, the outer edges of the slots being formed on a slant, as shown at 12^a, to engage the inclined edge of the wedge-key 13.

14 indicates wear-plates on the outer surface of bar 2.

In operation the device is secured to the wire fabric by removing the bar 2 from bar 65 1 and inserting the pins 5 through the meshes of the fabric. Bar 2 is then placed in position on pins 5 and the wedge-key 13 driven through slots 12. This will securely clamp the fabric between the bars, when the 70 fence may be stretched by means of a lever, windlass, or other suitable device, (not shown).

Having thus described my invention, what I claim is—

1. A wire-fabric clamp comprising two bars, pins secured to one bar, the other bar having holes to receive said pins, the end of each of said pins having a slot graduated in length with relation to the slot in each of the 80 other pins, and a single wedge-key engaging said slots, substantially as shown and described.

2. A wire-fabric clamp comprising two bars, one bar having rectangular recesses and holes therein, pins having rectangular shoulders engaging said recesses and threaded ends, threaded fastenings to engage said threaded ends, the other bar provided with holes to receive the other ends of the pins, 90 the end of each of the pins provided with a slot graduated in length with relation to the slot in each of the other pins, and a single wedge-key engaging said slots, substantially as shown and described.

3. A wire-fabric clamp comprising two bars, one bar having a longitudinal bead with rectangular recesses and transverse holes centrally of said recesses, pins having rectangular shoulders engaging said recesses and threaded ends fitting said transverse holes, threaded fastenings engaging said threaded ends, the other ends of said pins having longitudinal slots graduated in

length with relation to the slot in each of the other pins, and the other bar having a longitudinal groove to fit the bead on the first-mentioned bar and transverse apertures to receive the pins, and a single wedge-key to engage the slots in the pins, substantially as shown and described.

In testimony whereof I affix my signature in presence of two witnesses.

LUCINDA C. HINKLE.
